UNITED STATES PATENT OFFICE.

JESSE ENSIGN BRINKER AND CLAUDE PERKINS McNEIL, OF WHITING, INDIANA, AS
SIGNORS TO STANDARD OIL COMPANY, OF WHITING, INDIANA, A CORPORATION OF
INDIANA.

CANDLE-SHAPING MACHINE.

Application filed November 25, 1922. Serial No. 603,212.

To all whom it may concern:

Be it known that we, JESSE E. BRINKER and CLAUDE PERKINS McNEIL, citizens of the United States, residing at Whiting, in the county of Lake and State of Indiana, have invented a new and useful Improvement in Candle-Shaping Machines, of which the following is a specification.

The present invention relates to a candle shaping machine and will be fully understood from the following description, illustrated by the accompanying drawings, in which—

Figure 1 is a side elevation of the device embodying the present invention.

Figure 2 is a vertical sectional view through the device showing the plunger partly broken away.

Figure 3 is a sectional view on the line 3—3 of Fig. 2 showing the device in plan.

Figure 4 is a sectional view on the line 4—4, showing the trimming cutters.

Figure 5 is a sectional view on the line 5—5 of Fig. 2, showing the final shaping die.

Figure 6 is a sectional view similar to Figure 4, showing the different arrangement of trimming cutters for producing a pentagonal candle; and

Figure 7 is a view similar to Fig. 5 showing an arrangement of a shaping die for producing a pentagonal candle.

Referring more particularly to the drawings, the numeral 10 indicates the supporting table upon which the shaping device is mounted. The shaping device is formed with a tubular guide 11 in which is provided a lateral opening 12 for the insertion of the candle to be shaped. The tubular guide 11

is secured by a spider 13 to the tubular support 14 for the trimming blades 15, the arrangement of which corresponds to the shape to which it is desired to form the candle. The trimming blades 15 are

adjustably secured to the support 14 by means of the screws 16 which pass through slots formed in the blades. The support 14 is held by a spider 17 which is secured to a plate 18 mounted on the

table 10. Directly below the tubular support 14 is mounted the shaping die 19 in a block 20 secured to the table 10. The block 20 is provided with a central opening 21

for the passage of the shaped candle and suitable openings 22 are formed in the table 55 for the passage of wax shavings from the candle. A plunger 23, reciprocable in the tubular guide 11, is operated by the lever 24.

The candle to be shaped, which is usually 60 cylindrical, is inserted into the tubular guide 11 through the opening 12 with its tip down. The plunger 23 is then operated to force the candle downwardly. The candle first passes through the trimming cutters 65 15, which make an initial cut, partially reducing the cross section of the candle at the desired points. The candle then passes through the shaping die 19, which brings the cross section of the candle to the desired 70 form. The candle then drops into any suitable receiving device below the table 10, for example, the chute 25.

Figures 4 and 5 illustrate, respectively, an arrangement of trimming blades and of a 75 shaping die for forming a square candle from a cylinder candle. The trimming cutters, as shown in Fig. 4, partially reduce the cross section of the candle, leaving 80 curved surfaces at the reduced portions. The shaping cutters, as shown in Fig. 5, finally reduce the cross section of the candle to a square with slightly rounded corners. Figures 6 and 7 illustrate, respectively, an arrangement of trimming cutters and of a 85 shaping die for producing a pentagonal candle, the various parts being indicated in these figures by the same numerals as in Figures 4 and 5 with the suffix "a". It will be noted that these cutters operate upon the 90 candle in the same manner as the cutters and die shown in Figures 4 and 5 for the formation of a square candle.

We claim:

1. In a candle shaping machine, a tubular 95 guide provided with a side opening for the insertion of a candle, a tubular cutter mount axially aligned with said guide, trimming blades adjustably mounted thereupon, a shaping die axially aligned with the cutter mount, a plunger reciprocable in the tubular guide and mount, and means for operating the plunger for forcing a candle therethrough.

2. In a candle shaping machine, a sup- 105 port provided with an opening, a shaping

die mounted within said opening, a tubular cutter support secured to said first mentioned support, trimming cutters mounted on said cutter support, said cutter support and cutters being axially alined with the shaping die, a tubular guide in alinement with the cutter mount, a spider-like support for said

tubular guide secured to the cutter mount, a plunger reciprocating in the tubular guide and cutter mount, and means for operating the plunger for forcing a candle in succession therethrough. ¹⁰

JESSE ENSIGN BRINKER.
